Primary Examiner — Eric L Goodman*Assistant Examiner* — Steven J Czyz(74) *Attorney, Agent, or Firm* — Hamilton IP Law, PC;
Jay R. Hamilton; Charles A. Damschen(57) **CLAIM**

The ornamental design for a self-standing merchandise frame, as shown and described.

DESCRIPTION

FIG. 1 is a perspective view showing a self-standing merchandise frame;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines depict portions of the article that form no part of the claimed design.
